UNITED STATES PATENT OFFICE.

ISIDOR KITSEE, OF CINCINNATI, OHIO.

AUTOMATIC FIRE-ALARM.

SPECIFICATION forming part of Letters Patent No. 252,677, dated January 24, 1882.

Application filed October 25, 1881. (No model.)

To all whom it may concern:

Be it known that I, ISIDOR KITSEE, a citizen of the United States, residing at Cincinnati, in the county of Hamilton and State of Ohio, have invented a new and useful Improvement in Fire-Alarms, of which the following is a specification.

My invention relates to that class of fire-alarms and fire-extinguishers that are normally closed and inactive, but are brought into operation automatically during an incipient fire by the melting of fusible connections.

Referring to the drawings that accompany this specification, in which similar letters of reference in each figure indicate like parts, Figure 1 represents a bed-plate, to which a hinged or pivoted arm is connected, elevated by a fusible brace and fusible wire. Fig. 2 represents the same device as Fig. 1, provided with an explosive torpedo and striking-hammer. Fig. 3 is a view of my invention having an alarm-gong and clapper attached. Figs. 4 and 5 represent views showing forms of mounting the gong and clapper. Fig. 6 is a view of Fig. 2 wherein electric connections are substituted for the alarm-gong and clapper. Fig. 7 is a view of my invention wherein an attached armature and electro-magnet, a gong and clapper, and explosive torpedo are operated at one and the same time.

The objects of my invention are, in case of a fire in a building, to give automatically audible notice thereof; also, to extinguish fires by the automatic discharge of water or other fire-extinguishing fluids or gases.

Either form of my device may be used separately, or any or all of them in combination, and one or more of my devices can be arranged in the separate chambers of a building, so as to be actuated simultaneously or successively.

The principal elements of my invention consist of the device shown in Fig. 1, wherein A is a board or bed-plate, made of any suitable material, to which is hinged a swinging arm, C, retained in an elevated position by a fusible brace, D; but the arm C may be retained upward by means of a fusible wire, d, without departing from the scope of my invention. When the temperature rises to a given degree, sufficient to melt the fusible connection that re-

tains the arm C, as shown in the drawings, it falls by gravity and actuates whatever form of alarm may be attached to my device.

Fig. 2 represents my invention applied to the explosion of a torpedo. In this form of the device the bed-plate A is provided with an anvil, a, upon which is placed a fulminating torpedo, B, and the arm carries a hammer, c. It is manifest that when the arm C falls the hammer c will strike the torpedo B and explode it.

Fig. 3 represents my improved device adapted to sound an alarm-gong, wherein the arm C carries a clapper, c', and the bed-plate A carries a gong, A'. Both the gong and clapper are preferably mounted on oscillating springs c² c³, so that when the arm C descends the vibration of these springs will cause a continuous alarm to be sounded.

A form of mounting the gong and sounding-clapper is shown in Fig. 4, in which the swinging arm C has a short vertically-depend ing tube, C'. The tube is closed with a cap, c⁵, and has a central opening at its lower end to admit the free passage of the clapper-bearing stem c⁴. c⁴ c⁵ are internal guide-flanges, having central slots, through which the stem c⁴ can freely pass. The stem c⁴ is a simple piece of wire, having a stud-head, c⁶, to prevent its falling through the opening in the flanges c⁵, and has at its terminal end a gong-clapper, c'. The clapper-bearing stem is extended downward through the opening at the lower end of the tube C' by means of an extended helical spring, c⁷, which is coiled round the rod nearly its full length. The gong A' may be similarly mounted on the bed-plate A.

Another practical manner of mounting the gong is illustrated in Fig. 5. Upon the bed-plate A is a short vertical post, a². A helical spring, a³, surrounds the post and extends beyond it upwardly, in order to support the inverted cup A². A² is a cover, in the form of an inverted cup, having a stem, a⁴, upon which the gong A' is firmly adjusted. The inverted cup fits loosely over the post a², and is kept upwardly extended therefrom by means of the spring a³. The arm C, hinged or pivoted to the bed-plate A at a⁴, is kept elevated by fusible connections, as hereinbefore described, and when falling the clapper c' strikes the gong.

The sudden percussion causes retraction of the springs a^3 and c^7 , and the movable parts controlled by these springs are set in motion, causing the gong and the clapper to approach and 5 recede from each other in continuous vibration, thus striking a succession of blows and sounding repeated alarms.

Fig. 5 is a modification in which the helical springs are kept compressed by means of fusible plugs or keys E. This character of key can be used to retain in position the movable parts of any of my devices, and in all of my descriptions, when speaking of a fusible support or fusible wire, I desire to be understood that 5 a fusible retaining key or plug, E, can be substituted without departing from my invention.

Fig. 6 is a device containing the operative elements of Fig. 1, in which an electro-magnet is substituted for the attached operative devices shown in Figs. 2 and 3, the arm C being provided with an armature having the necessary wires attached to complete a circuit, which is normally opened and closed, as the case may be. The falling of the arm C makes or breaks 5 the circuit, thus giving the alarm to suitable connections, bringing into action any of the operative devices with which the electric current is connected.

I will state that in the electric devices it is 5 preferable to have a vibrating armature, so as to maintain a constant alarm when the current-wire is operated upon.

Another part of my invention consists in devices which discharge a projectile, preferably explosive, from the barrel of a stationary gun against a detonating-nipple affixed to a target.

Another part of my invention consists in giving an audible alarm by the discharge of compressed air through valves, control of which is maintained by fusible connections, and further consists in novel devices for ejection of fluid or gas from reservoirs kept normally closed by means of fusible connections; but it is not 5 necessary herein to describe in detail or specifically claim the guns, the air-alarm, or pneumatic alarm, or explosive torpedo devices, as they are included in separate applications for Letters Patent, although it is my intention to 5 use them in combination with the alarm devices herein described and claimed.

The manner of operating the several characters of devices herein claimed in combination is represented in Fig. 7.

I am aware that thermostats and fusible connections for automatic fire-alarms are not new with me, and I lay no claim broadly thereto.

I am aware, also, that electric local alarms 5 actuated by rupturable connections have been used before; but the electric alarms I herein describe and claim operate not only local an-

nunciators, but also by attached current-wires actuate alarm devices of any suitable character beyond the building where the primary devices are set in motion in the manner described—as, for instance, to police or fire stations, or the residence of the owner of a building where an incipient fire occurs, in which my devices are located.

Having now fully described my invention, what I claim is—

1. In an automatic fire alarm, the bed-plate A, provided with swinging arm C, having suitable alarm devices attached thereto, in 75 combination with fusible brace D, as and for the purpose intended, substantially as described.

2. The combination, in an automatic fire-alarm, of an armature and electro-magnet connected to current-wires, with the fusible brace D, and bed-plate A, provided with sounding-alarm, said bed-plate further provided with swinging arm C, carrying a spring-borne clapper and suitable for operating both electric 85 and other alarm devices, substantially as described.

3. In an automatic fire-alarm, the bed-plate A, carrying spring-supported gong A', and swinging arm C, provided with spring-borne 90 clapper c', in combination with fusible brace D, substantially as described.

4. In an automatic fire-alarm operated by melting of fusible connections, the combination of the gong A', provided with inverted sliding cup A², and mounted on a vertical post, a², provided with helical spring a³, with tube C', having interior flanges, c⁵, and clapper c', controlled by helical spring c⁷, substantially as described.

5. In an automatic fire-alarm operated by melting of fusible connections, the combination of the bed-plate A, having gong A', provided with inverted sliding cup A², and mounted on a vertical post, a², provided with helical spring a³, with fusible retaining-key E, and swinging arm C, depending tube C', having interior flanges, c⁵, and further provided with gong-clapper c', controlled by helical spring c⁷, substantially as described.

6. In an automatic fire-alarm operated by melting of fusible connections, the bed-plate A, provided with spring-supported gong A', and electro-magnet R, connected with current-wires, in combination with fusible brace D, 115 and swinging arm C, provided with armature r, and gong-clapper c', adapted, when operated, to simultaneously sound the gong and make and break electric communications, substantially as described.
